BATTERY CHARGER

Chester J. Abend, Camillus, and William Andrew Morrison, Syracuse, N.Y., assignors to SCM Corporation, New York, N.Y., a corporation of New York

Filed July 18, 1963, Ser. No. 75,872

Term of patent 14 years

(Cl. D26—15)

FIGURE 1 is a front perspective view of a battery charger showing our new design;

FIGURE 2 is a front elevation view thereof;

FIGURE 3 is a rear elevation view thereof; and

FIGURE 4 is a left end elevation view thereof to an enlarged scale.

The front and rear faces of the battery charger are scored to harmonize with the knurled knob.

We claim:

The ornamental design for a battery charger, substantially as shown and described.
